UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

CAR-DOOR LATCH.

Original application filed January 30, 1922, Serial No. 532,734, now Patent No. 1,455,520, dated May 15, 1923. Divided and this application filed July 10, 1922. Serial No. 573,847.

To all whom it may concern:

Be it known that I, ARGYLE CAMPBELL, a citizen of the United States, residing at Chicago, in the county of Cook and State of Illinois, have invented a certain new and useful Improvement in Car-Door Latches, of which the following is a full, clear, concise, and exact description, reference being had to the accompanying drawings, forming a part of this specification.

My invention relates to improvements in car door latches, and is especially adapted for locking the doors of railway dump cars.

This application is a division of my co-pending application Serial No. 532,734, filed January 30, 1922, now patent No. 1,455,520, granted May 15, 1923.

The object of my invention is to provide simple and efficient means for locking the doors in closed position.

Another more specific object of my invention is to provide a simple and reliable means for holding the pivot of the latch in assembled relation with the latch carrying bracket.

Other objects of the invention will more clearly appear from the description and claims hereinafter following.

In the drawings forming a part of this specification, Figure 1 is a side elevation of part of a dump car showing my improved latch. Figure 2 is an enlarged transverse sectional view corresponding substantially to the section on the line 2-2 of Figure 1. Figure 3 is a side elevational view, on a still larger scale, of my improved door locking latch mechanism. Figure 4 is a horizontal sectional view substantially on the line 4-4 of Figure 3. Figure 5 is a vertical sectional view corresponding substantially to the section line 5-5 on Figure 4. And Figure 6 is a transverse sectional view corresponding substantially to the line 6-6 on Figure 5.

In said drawings, the car is shown as provided with an underframe comprising a ridge shaped center sill 10, cross members, or diaphragms, or needle beams 11 and 12, angle iron side sills 13, side walls 14, side stakes 15, diagonal braces 16, fixed floor sections A, drop bottom doors B, and longitudinally extending cover plates or boards 18 over the center sill.

As shown in Fig. 2, the floor doors B are

pivoted along their inner edges as indicated 55 at 19 to suitable hinge butts preferably attached to the center sill, or to the latter and the cross members of the underframe. Each of the doors B preferably consists of a plurality of longitudinally extending 60 boards or planks secured together on the upper sides by a plurality of plates or straps, and braced on the underside by a pair of transversely extending beams 21. Each of the latter, at the outer free edge 65 of the door, is downwardly deflected as indicated at 21^a and then extends outwardly horizontally as indicated at 21^b beyond the plane of the side wall 14, for the purposes hereinafter described.

Beneath each door, as shown in Fig. 2, I locate a longitudinally extending bar 22, preferably composed of wood on account of its yielding qualities to lessen the shocks when the door strikes it. Each of said bars 75 22 is supported at its ends by means of a U-shaped strap 23 shaped to snugly fit and receive the bar 22, the upper ends of the side arms of the strap being twisted at right angles to the bottom central portion, as indicated at 23^a-23^b, and the latter in turn being riveted or otherwise rigidly secured to the adjacent needle beam or cross member 11.

Preferably the bars 22 are provided with 85 suitable hardened wear plates 24 on their upper sides in line with the door braces 21 so that wear on the bars is minimized and the shock is transmitted to the door through the braces 11. The stop arrangement which 90 I have shown is more or less resilient, is efficient in operation, superior to the usual angled flange employed for a similar purpose, and the strap attachment permits of the doors being stopped at any desired point, 95 it being evident that the straps are extended below the bottom edges of the cross members or diaphragms. It will also be noted that the straps are placed so as to extend at right angles to the plane of the door 100 when the latter is in its opened position, thus placing the strap purely under tension and rendering it most efficient.

In order to eliminate the use of expensive shafts and the usual flexible door raising and lowering devices, I employ locking latches, two for each door, as shown in Fig. 1. The details of one of said latches,

which are arranged right and left so as to swing toward each other as clearly shown in Fig. 1, are best illustrated in Figs. 3, 4, 5 and 6. Each of said locking devices comprises, broadly, a bracket or support C; a lever latch D; and a locking cam E.

The bracket C, preferably a casting, is provided with a main back wall or web 30, which, when the bracket is in position, bears 10 against and is secured to the side wall structure of the car as by a series of three rivets 31-31. To provide a housing and also to prevent outward bending or movement of the latch and locking cam, the bracket C 15 is formed with an outer wall or web 32 united to the main wall or web 30 by flanges 33 and 34. The contour of the web or wall 32 is irregular and preferably of the outline shown best in Fig. 3. The latch and locking cam are housed between the walls or webs 30 and 32, the swinging movement of the lever latch D in a closing or operative direction being limited by said flange 33, as 20 shown in Fig. 5. The swinging movement 25 of the cam E to its inoperative position, is likewise limited by the same engaging the flange 34.

I have provided a novel and efficient means for pivotally supporting the latch 30 and cam. In the back wall or web 30 of the bracket C are provided depressions or circular recesses 35 and 36, the back wall at 35 these points being thickened to allow for said recesses 35 and 36 without weakening the casting. The recesses 35 and 36 accommodate the heads 37 of heavy pivot pins 38 and 39 for the latch and cam respectively, the shanks of said pins being extended horizontally outwardly through alined openings 40 in said back wall 30 and outer wall 32 as clearly illustrated in Fig. 4. In this manner the pivot pins 38 and 39 are positively held against displacement after the locking device is in position, inasmuch as the heads of 45 the pins are confined between the bracket and the adjacent fixed portions of the car structure. With this arrangement, the pins are stronger and less subject to bending and shear than if the same were extended entirely through the bracket into the side wall 50 structure of the car. The latch lever D is formed with a shank having the upper portion thereof 40 sloping downwardly and from its pivotal support toward the opposite latch of the same set, the lower portion 55 of the shank as indicated at 41 extending vertically when the latch is in operative position. At the bottom of the shank, is formed a bearing or locking face 42 which 60 is curved on a relatively long radius about a center eccentric to the axis of the pivotal connection of the latch so that said curved bearing face 42 when it is pushed home against a corresponding curved bearing face 65 43 provided on the bottom of a block 44

secured to the outer end 21^b of the door brace, will have a wedging effect in pushing the door to fully closed position. It will also be noted that the shank of the latch D is of right angular cross-section with one 70 flange 45 extending in planes transverse of the car and the other or outer flange 45' extending parallel to the car and overlapping the end of the door brace and block 44 when in operative position. 75

The locking cam E is of the usual type, having a cam surface adapted to engage with a flat surface 46 on the portion 40 of the shank of the latch lever.

As will be understood by those skilled in the art, the doors are adapted to be lifted by hand or by means of a suitable lever engaged with a socket or bracket on the under-side of the door and lifted to closed position. As the doors approach their closed position, the projecting ends 21^b engage the beveled lower ends 47 of the latch levers D thereby pushing the latter so as to clear the extensions 21^b until the latter are sufficiently elevated for the locking faces 42 of the latch levers to swing under the locking faces 43 under the influence of gravity.

With my arrangement of locking latches, it is evident that the expense for the door operating means is very materially reduced 95 as compared with prior arrangements, commonly employed on general service cars, so that this reduction of the expense in conjunction with the reduced cost of the doors and fittings, makes the entire car an extremely inexpensive one to manufacture.

I have herein shown and described what I now consider the preferred manner of carrying out the invention, but the same is merely 105 illustrative and I contemplate all changes and modifications that come within the scope of the claims appended hereto.

I claim:

1. In a car, the combination with a pivoted dump door having a projection from one of its edges; of means for locking said door in closed position comprising, a bracket secured to a fixed part of the car, a shouldered latch engageable with said projection and a headed pin for pivotally supporting said latch from said bracket, said pin extending through the bracket and having its head confined between the inner face of the bracket and the adjacent portion of the car. 110
2. In a car, the combination with a pivoted dump door having a projection from one of its edges; of means for locking said door in closed position comprising, a bracket secured to a fixed part of the car, a shouldered latch engageable with said projection, said latch being pivoted to the bracket; a locking cam engageable with said latch to hold it in operative position, and a headed pin for pivotally supporting said locking cam from 125 said bracket, said pin extending through the 130

- bracket and having its head confined between the inner face of the bracket and the adjacent portion of the car.
3. In a car, the combination with a pivoted dump door having a projection from one of its edges; of means for locking said door in closed position comprising, a bracket secured to a fixed portion of the car, a shouldered latch engageable with said projection, a locking cam engageable with the latch, and headed pins for pivotally supporting the latch and locking cam, each pin extending through the bracket and having its head confined between the inner face of the bracket and the adjacent portion of the car.
4. In a car, the combination with a pivoted side dump floor door having extensions from its free edge extending outwardly beyond the side wall of the car; of means for holding said door in closed position, said means comprising brackets secured to the outer face of the car wall and shouldered latches pivotally attached to said brackets adapted to engage said projections, said latches having shanks of angular cross-section.
5. As an article of manufacture, a latch for pivoted doors, said latch comprising, a bracket having an inner wall and an outer wall spaced therefrom to form a housing, a shouldered lever pivotally supported from said bracket between said inner and outer walls thereof and depending below the bracket and adapted to fall to operative position under the influence of gravity, a locking cam cooperable with said lever to hold it in operative position, and bodily detachable pivot pins for said lever and locking cam, said pivot pins being provided with retaining means adapted to engage one side of the bracket and a portion of the surface to which the bracket is secured.
6. In a door device for railway cars, the combination with a hinged drop door having a hook-engaging seat formed thereupon, of a door-supporting hook pivoted upon the car body and arranged for supporting co-operation with the said seat, the said hook having a shank portion and a supporting ledge below the shank portion arranged for engagement with the said door seat, there being an integral shroud of metal connecting the said ledge with the said shank portion, the said shroud being arranged to one side of the said ledge.
7. In a door device for railway cars, the combination with a hinged drop door having a hook-engaging seat formed thereupon, of a door-supporting hook pivoted upon the car body and arranged for supporting co-operation with the said seat, the said hook having a shank portion and a supporting ledge below the shank portion arranged for engagement with the said door seat, there being an integral shroud of metal connecting the said ledge with the said shank portion, the said shroud being arranged to one side of the said ledge and outwardly of the said seat on the door.
8. A locking device for car doors embodying a base with inner and outer spaced walls comprising a housing, a hook pivotally mounted between said walls, an end wall connecting the said inner and outer walls, the said end wall extending around the top of the hook in an arcuate path.
9. A locking device for the drop doors of railway cars, embodying a bracket with integral inner and outer walls and an integral connecting wall, a hook pivoted between the inner and outer walls, the said connecting wall extending at an angle with the general line of the bracket and following the contour of the forward edge of the hook, and bracket-securing rivets extending through the said inner wall, the same being arranged along the said connecting wall.
10. A locking device for the drop doors of railway cars, embodying a bracket with a base portion, an outer wall integral with and spaced from the said base, an integral connecting wall, a hook pivoted between the base and the outer wall and lying along one side of the connecting wall, a dog pivoted to the bracket to the rear of the hook, and a plurality of rivets connecting the bracket to the car, the said rivets passing through the said base and some thereof being located along one side of the said connecting wall and the hook and others thereof being located to the other side of the said connecting wall and the hook.

In witness that I claim the foregoing I have hereunto subscribed my name this 24th day of June, 1922.

ARGYLE CAMPBELL.
